Primary Examiner—M. N. Pandozzi**Attorney, Agent, or Firm—Harold H. Dutton, Jr.; W. Charles L. Jamison; Diane F. Liebman****[57] CLAIM**

The ornamental design for a bottled beverage dispenser, as shown and described.

DESCRIPTION

FIG. 1 is a perspective view of a bottled beverage dispenser showing my new design;

FIG. 2 is a left side view thereof; The right side is a mirror image of the left side;

FIG. 3 is a front view thereof;

FIG. 4 is a rear view thereof;

FIG. 5 is a top view thereof; and,

FIG. 6 is a bottom view thereof.

The broken line showing of a beverage bottle in FIG. 1 is for illustrative purposes only and forms no part of the claimed design.
